TOOLHOLDER FOR THE SADDLE OF
MACHINE TOOLS

Carl Rebmann, Aarau, Switzerland

Application August 30, 1944, Serial No. 551,891
In Switzerland June 30, 1943Section 1, Public Law 690, August 8, 1946
Patent expires June 30, 1963

2 Claims. (Cl. 29—98)

1

The present invention relates to a tool-holder for the saddle of machine tools, for example of lathes, milling machines and the like.

The present invention provides a tool-holder device which permits to set up various interchangeable tools or revolving tool boxes.

In accordance with the present invention, the tool-holder device comprises a locking device which can be operated independently of the clamping of said holder in its operative position in such a manner that in the locking position of said device the fixed tool or revolving tool-box is locked in its position whilst with the locking device in its open position, said tool or revolving tool box is released so as to permit to have its position changed or to be removed from said tool-holder.

Hence it is not only possible to set up interchangeably various individual tools in the tool-holder, but also simultaneously a number of various tools clamped in the revolving tool-box, and each of said tools can be brought into operative position on its turn by a rotary motion of said revolving tool-box.

The invention itself both as to structure and mode of operation will be best understood from the following detailed description of a preferred embodiment of the invention shown by way of example in the accompanying drawing. In this drawing:

Fig. 1 is a view in side elevation of the tool-holder with its locking device;

Fig. 2 is a view in plan of the tool-holder in the position for working the interior of a work-piece; and

Fig. 3 a view in plan of the tool-holder in the position for longitudinal working of a work-piece;

Fig. 4 shows a view in vertical longitudinal section of the tool-holder body along the line IV—IV in Fig. 2;

Fig. 5 shows a view in horizontal longitudinal section of the tool-holder body along the line V—V in Fig. 1 with the revolving tool box set up;

Fig. 6 is a front view of the tool-holder;

Fig. 7 shows the bolt of the locking device in longitudinal elevation;

Fig. 8 a view in longitudinal section thereof;

Fig. 9 a front view thereof with and without the locking fork respectively;

Fig. 10 shows a tool for interior working to be set up in the tool-holder in a view of longitudinal elevation;

Fig. 11 is a view in longitudinal elevation of a

2

revolving tool box to be set up in the tool-holder and

Fig. 12 a front view thereof;

Fig. 13 shows a modification of the tool-holder in a view of horizontal section.

In the drawing, only the tool-holder in its utilization on a lathe is illustrated and the saddle or carriage on which it is to be clamped has been omitted as known per se.

10 Referring now to Figs. 1 to 3, the tool-holder illustrated therein comprises a block 1 of rectangular transverse section provided with a hole 2 for the clamping on the carriage of the lathe, the clamping screw of which is to be inserted in the hole 2. Further, the block 1 is provided with an eccentrically arranged longitudinal bore of conical shape 3 for receiving the shank 5 of a revolving tool-box 4, said shank being designed as a Morse's cone. The shank 5 has a circular 20 recess 6 into which is protruding the locking fork 8 of the locking device. Said fork 8 is rotatably secured on the inner end of the locking bolt 10 arranged in the block 1 transversely with respect to the bore 3, and the pin 9 holding the 25 fork 8 is pressed eccentrically into the front end of the bolt 10 as shown in Fig. 9. The locking bolt has on its circumference a Z-shaped guide-groove 11 with the sections m, n and o (Figs. 7 and 8) and a guide-pin 12 secured in the 30 block 1 is protruding into said groove. Further, the locking bolt 10 has a circular recess 13 into which is engaged a plate spring 14 laterally secured on the block 1 by means of the head screw 18. A handle lever 7 is inserted into a trans- 35 verse bore of the bolt 10 in order to operate the locking device.

The revolving tool box 4 shown in Fig. 5 is provided with four slots a, b, c and d open at the front side and into which tools of the usual type 40 can be inserted and clamped by means of screws (not shown).

On the front face of said tool-holder are fastened four pins 16, arranged at the angles of a square and which are to be inserted into four 45 corresponding holes of the revolving tool box in order to prevent an accidental rotary motion of said tool box and to bring the tools always positively in the same position. Obviously a plurality of revolving tool boxes of various size and 50 tool-equipment may be provided for insertion into the tool holder. However, individual tools may also be set up into the tool holder. For example the turning tool 17 intended for turning out works can be set up instead of a revolving tool box, the 55 shank of said turning tool 10 being similarly

performed as a Morse's cone 5 fitted into the bore 3 and provided with the circular recess 6. The tool-holder can be clamped on the carriage as desired in a longitudinal, transversal or oblique direction with respect to the lathe bed. The setting up in a longitudinal direction is suitable for the working of the interior of work-pieces whilst the setting up in transversal direction is favorable for the working of longer work-pieces. In the latter case, the tool-holder is to be turned by 180° about its axis and 90° about the clamping screw of the carriage rest.

The mode of operation of the aforescribed tool-holder will now be described:

The tool-holder is set up into the carriage rest of a lathe, by inserting the clamping screw of the latter into the hole 2. The locking device has been brought into the release position by means of the lever 7 against the pressure of the spring 14, which has been tensioned by shifting the bolt 10 outwardly, and the Morse's cone 5 of the revolving tool box 4 can now be inserted from the front side into the bore 3. In this position of the locking bolt 10, the guide pin is engaged in the section m of its groove 11 and thereby locks the bolt so that it cannot be shifted inwardly by the spring 14. Now the bolt 10 is oscillated in a clockwise direction by means of the lever 7 (Fig. 1) so that the guide pin 12 leaves the groove section 11m and enters into the longitudinal section 11n, whereupon the spring 14 will bias the bolt 10 inwardly into the hole of the block 1 until the guide pin 12 reaches the groove-section 11o. The fork 8 is thereby shifted into the circular recess 6 of the shank 5, pulls it fully into the bore 3 and effectuates its locking, the pins 16 maintaining the tool-holder in its exact radial adjustment.

When instead of the set tool another tool of the revolving tool box is to be brought in operative position, the lever 7 is oscillated to the left (Fig. 1) so that the fork 8 drives the shank 5 out of the bore 3 and thereby releases the revolving tool-box. The lever 7 is only oscillated so far as to bring the four holes of the revolving tool box 4 out of engagement with the pins 16 of the tool-holder. The shank 5 is now only loosely engaged in the bore 3 and has a sufficient play to permit a rotary motion of the revolving tool box to bring it into the desired position. Thereupon, the lever 7 is oscillated back locking thereby the shank 5 again in its new adjustment in the bore 3.

When the revolving tool box is to be replaced by another one, the lever 7 is again oscillated to the left (Fig. 1) until the bolt 10 can be retracted so far that its fork 8 fully leaves the recess 6, and by the continued oscillation, the guide pin 12 is engaged in the groove section 11m and locks the bolt 10. Now the revolving tool box 4 can be taken off and another one inserted and locked again, the operation being the same as above described. Instead of a revolving tool box an individual tool could also be inserted in the same manner such as the turning-tool 17 shown in Fig. 10.

In opposition to the well known tool-supports with a noninterchangeable revolving tool box and tool-rest the tool-holder according to the present invention affords the advantage that a changing of the tool or revolving tool-box is possible without requiring to remove the tool-holder and to proceed to a new setting of the carriage each time when a changing is effectuated.

In the embodiment illustrated in Fig. 13, the

block 31 of the tool-holder is designed as above described with the pins 16 and the revolving tool box 4 is equally performed in a similar manner with a Morse's cone shank 5 provided with the circular recess 6 such as to fit into the longitudinal bore 33. A key 30 is removably inserted into a vertical hole in the immediate vicinity of the bore 33 and the upper end of said key is bent horizontally such as to provide an oscillating lever 37. The key bits protrude into the circular recess 6 of the shank 5 and its length is such as to permit a shifting of said shank over the length of the pins 16. When it is desired to oscillate the revolving tool box in order to set another tool into operating position, the lever 37 is to be oscillated to the left whereby the key bits 30 drives the shank 5 out of the bore 33 and the pins 16 out of engagement with their respective holes thereby permitting the revolving box tool to be oscillated to the desired setting position. Thereupon the lever 37 is oscillated backwardly whereby the shank 5 is driven into the bore 33 and blocked again.

When it is desired to substitute another revolving tool box or an individual tool to the revolving tool box 4, the key 30 is oscillated to the left and drawn out of its hole so that the shank 5 can be drawn out of the bore 33. Thereupon the other revolving tool box is put in place, the key 30 is again inserted into its hole and the lever 37 oscillated backwardly so as to block the shank 5 again.

I do not limit my invention to the structure shown and described as modifications, within the scope of the appended claims, may be made without departing from the spirit of my invention. Having thus described my invention what I claim as new and desire to secure by Letters Patent is:

40. 1. A tool holder comprising a block means, tool means having a portion receivable and longitudinally movable in said block means, a transverse element rotatably and axially movable disposed in said block means, an eccentric engaging means rotatably connected with said element and adapted to engage said portion of said tool means, guide means comprising a groove on said element, said groove having an axially extending portion and two circumferentially extending portions extending in opposite directions from the ends of said axially extending portion, and a pin rigidly connected with and permanently extending from said block means into said groove and, upon engagement of one of said circumferential portions, affording rotation exclusively of said element to cause said engaging means to move said tool means or, upon engagement of said pin and said axial portion, affording axial movement exclusively of said element to cause engagement and disengagement of said engaging means and of said tool means.

2. In a tool holder, the combination of a tool holding member having a spindle-like extension, a block having a bore accommodating said extension, said extension having an annular recess, locking means comprising an operating member rotatably inserted in said block and having an axis positioned substantially at a right angle with respect to said bore and having an end portion, a head member comprising a fork-like portion straddling said extension in said recess and having a stem portion rotatably and eccentrically inserted in said end portion, said operating member having a groove having an annularly extending portion, an axially extending

portion extending from one end of the aforesaid portion, and another annularly extending portion extending from said axial portion in a direction opposite to said first portion, and a pin connected with said block and extending into said groove and determining in cooperation with said groove the movement of said operating member.
